FLUID COUPLING

Benjamin A. Swennes, Rockford, Ill., assignor to
 Borg-Warner Corporation, Chicago, Ill., a corporation of Illinois

Application April 5, 1941, Serial No. 387,016

3 Claims. (Cl. 103—115)

1

This invention relates to hydraulic power transmitting devices such as fluid couplings.

The principal object of this invention is to provide a fluid coupling which is economical to manufacture, and which will introduce the least amount of obstructions to the flow of fluid, thereby providing maximum efficiency.

A fluid coupling commonly comprises a pair of opposed outer shells with each shell having disposed therein a series of spaced radially extending vanes, and it is an object of my invention to provide an improved vane construction whereby the vanes may be easily assembled in their proper positions in the shells and without the use of holding fixtures, if desired. Each outer shell of a fluid coupling may have disposed therein an inner core section and it is a further object of my invention to provide an improved vane construction wherein the vane forming members when in assembled relation in a shell also form the inner core section in the shell. More particularly, it is an object of my invention to provide an improved vane construction whereby the vanes and inner core section are formed by members which each form two adjacent vanes or at least a portion of each of the adjacent vanes and the portion of the core section between the two vanes.

It is another object of my invention to provide a fluid coupling constructed such that it may be easily disassembled to allow the parts of the coupling which tend to wear on rotation of the driving and driven portions of the coupling relative to each other to be replaced and in particular to allow replacement of the seal which normally holds the fluid in the coupling and parts in contact therewith which rotate relative thereto on relative rotation of the driving and driven portions of the coupling.

These and other objects and features of the invention will become apparent from the following description when considered with the accompanying drawings. The several figures comprise:

Fig. 1 showing a fragmentary elevation of an assembled shell and vane of the novel fluid coupling;

Fig. 2 showing a side elevation in section of a complete coupling incorporating a view of the shell and vane taken along lines 2—2 of Fig. 1;

Fig. 3 showing a blank from which a pair of vanes and a core section are formed;

Fig. 4 showing the completely formed double-vaned section;

Fig. 5 showing a group of double-vaned sections united to form a sector of vanes; and

2

Figs. 6 and 7 showing respectively front and side elevations in section of a shell into which the vanes fit.

Referring now to the drawings for a detailed description of the invention, the fluid coupling is comprised of two opposed shells 10 forming a torus, each shell having therein a series of radially extending vanes 11 bounded on one side by shell 10 and on the other by a core ring shell 12. Each shell is attached respectively to a driving shaft 18 and to a driven shaft 31, with a fluid-tight casing surrounding the coupling and with the coupling slightly less than completely filled with suitable fluid, all as hereinafter described.

The method by which the coupling is formed is as follows:

Each vane 11 is comprised of two thicknesses of metal having the shape shown in Fig. 4. These vanes are formed as units by stamping sheet metal into a blank having the shape shown in Fig. 3. The blank is comprised of two symmetrical crescent-shaped portions 13 and 14 having curved edges 15 and 16 defining respectively the outer and inner boundaries of the fluid circuit, and a substantially trapezoidal central section 17 which is joined at its corners to crescent-shaped sections 13 and 14. In the next operation, the blank is placed in a punch press and the crescent-shaped sections 13 and 14 are bent backward as shown in Fig. 4, so as to coincide with radial planes of the finished coupling. Central section 17 is then curved toward the sections until it abuts edge 16 of each vane. The resulting unit is a U-shaped sector of the fluid coupling containing two spaced half thickness of vanes lying in radial planes, each unit being sufficiently rigid to hold the spacing between vanes and to withstand subsequent handling without deformation.

Suitable half toroidal sections 10 such as shown in Figs. 6 and 7 are then formed to constitute the outer shells of the fluid coupling halves. This does not involve any new principles of operation and can be accomplished in any proper sized press.

Next the vanes are assembled in the shell. This may be done by pre-assembling sections as shown in Fig. 5, the sections comprising groups of units such as shown in Fig. 4 which have been secured together either by means of a fixture or by a preliminary welding action. If the group has already been welded, then it is merely placed into a shell along with enough other groups to completely fill the shell, and the entire assembly may then be united, preferably by a hydrogen brazing process, to form a unitary whole. Alternating

tively, the shell may be filled with individual units which have not been united into groups, and after the individual units are properly located within the shell with respect to one another so as to form a uniform and symmetrical structure, the whole is then hydrogen-brazed into an integral unit. Each U-shaped sector comprises a core ring shell section which is an even divisor of the complete core ring shell 12, and when the sectors are assembled in the half toroidal shells 10, the U-shaped sectors completely fill the shells 10.

Since each double-vaned unit will hold its shape, it is unnecessary to use holding fixtures to maintain the vanes in their proper relation with respect to the shell while the brazing process is being conducted. Each unit is so formed originally that when the proper number is assembled, the entire shell will be completely filled and each unit will be held in place by its adjacent units.

I have found that with a vane shape as shown in Fig. 2 and a core ring, the driving and driven portions of the coupling may be made identical. Thus, it is unnecessary to have more vanes on one member than on the other as is customarily done, and the same unit may be used interchangeably for the driving half or the driven half.

The hydrogen brazing process is a well known process and will not be described here in detail. It will suffice to state that the process comprises placing copper or a suitable copper alloy along the joint to be welded and then heating the copper in a hydrogen atmosphere until it flows into the joint and forms a firm bond. In the case of the fluid coupling, after the vanes are in place and the copper is laid along the joint, the coupling halves are passed through a furnace where they are heated until the bond is formed.

It will be noted that it is unnecessary to pierce the shell in order to secure the vanes thereto and accordingly it is possible to omit a shroud for the driving vanes and to secure the shell of the driving section to the flywheel by attaching it thereto around the outer periphery of the shell.

The completely assembled coupling is shown in Fig. 1. The drive shaft 18 is bolted to a casting 19 to which is welded a housing 20, which encloses the driving half 21 and driven half 22 of the coupling. Driving half 21 is welded to a flange 23, which in turn is bolted to housing 20, and serves to transmit the drive from the housing to the driving half.

Casting 19 is formed with a shoulder 24 against which abuts a bearing 25, the latter being held in place by a snap ring 26. Said bearing supports and positions a hub 27 to which is riveted a flange 28 welded to driven half 22. Hub 27 has internal splines 29 engaging splines 30 on a driven shaft 31, said splines 30 having a shoulder 32 which abuts the end of hub 27. Thus, forward thrusts from driven shaft 31 are taken on shoulder 32 and transmitted to bearing 25. Thrusts in the opposite direction are taken by a snap ring 33, which bears against a curved notch 34 in splines 30. To remove shaft 31 from the coupling all that is required is a light rearward blow on shaft 31 or some associated part.

Also secured to housing 20 is a plate 35 which serves as an abutment for a seal 36 of a well-known bellows type. It will be noted that seal 36 bears against a hardened ring 37, which is threaded on hub 27 and may be replaced when worn without replacing the entire hub. Furthermore, plate 35 is of such size that when it is removed, and seal 36 is withdrawn with it, ring 37 can be

easily reached and removed without further disassembling the coupling.

It is understood that the foregoing description is merely illustrative of a preferred embodiment of the invention, and that the scope of the invention, therefore, is not to be limited thereto, but is to be determined by the appended claims.

I claim:

1. A fluid coupling member comprising an annular shell, an annular core shell inside and spaced from said first named shell and a plurality of spaced radial vanes inside said first named shell and extending between the two shells, said core shell and said vanes being formed by a plurality of elements, each of said elements comprising a section of the core shell and a pair of spaced vanes integral with the core shell section, said elements being disposed in contact with each other side by side in said first named shell.
2. A fluid coupling member comprising an annular shell, an annular core shell inside and spaced from said first named shell and a plurality of spaced radial vanes inside said first named shell and extending between the two shells, said core shell and said vanes being formed by a plurality of elements, each of said elements comprising a section of the core shell and a pair of spaced vane portions integral with the corner regions of the core shell section, said elements being disposed in said first named shell side by side with two adjacent vane portions of the elements being in face to face contact and together forming a single vane extending between the shells.
3. A fluid coupling member comprising a substantially semi-toroidal shell, a substantially semi-toroidal core shell inside and spaced from said first named shell and a plurality of spaced radial vanes inside said first named shell and extending between the two shells, said core shell and said vanes being formed by a plurality of elements, each of said elements comprising a section of the core shell and a pair of spaced vanes integral with the core shell section, said elements being secured in said shell in position side by side and in contact with each other, each of said elements being adapted to be self-supporting when placed individually in the shell with its core section in position to form a part of the complete core shell before being secured therein, whereby to facilitate securing the elements in the shell.

BENJAMIN A. SWENNES.
